CLAIM

The ornamental design for a combined swing for infant and removable canopy therefor, as shown and described.

DESCRIPTION

FIG. 1 is a front perspective view of a combined swing for infant and removable canopy therefor showing the design of my invention;

FIG. 2 is a front elevational view of my swing with the canopy attached;

FIG. 3 is a rear elevational view of my swing with the canopy attached;

FIG. 4 is a right side elevational view with the canopy attached;

FIG. 5 is a top plan view of my swing with the canopy attached;

FIG. 6 is a left side elevational view of my swing with the canopy attached;

FIG. 7 is a bottom plan view of my swing with the canopy attached;

FIG. 8 is a front perspective view of the swing of FIG. 1 with the canopy removed;

FIG. 9 is a front elevational view of the swing of FIG. 1 with canopy removed;

FIG. 10 is a rear elevational view of the swing of FIG. 1 with canopy removed;

FIG. 11 is a right side elevational view of the swing of FIG. 1 with canopy removed;

FIG. 12 is a top plan view of the swing of FIG. 1 with canopy removed;

FIG. 13 is a left side elevational view of the swing of FIG. 1 with canopy removed; and

FIG. 14 is a bottom plan view of the swing of FIG. 1 with canopy removed.
